UNITED STATES PATENT OFFICE.

OLAF A. ANDERSON AND JOHN M. MACRAE, OF DETROIT, MICHIGAN.

PUMP.

Application filed April 14, 1922. Serial No. 552,506.

To all whom it may concern:

Be it known that we, (1) OLAF A. ANDERSON and (2) JOHN M. MACRAE, citizens of the United States of America, residing at Detroit, in the county of Wayne and State of Michigan, have invented certain new and useful Improvements in Pumps, of which the following is a specification, reference being had therein to the accompanying drawings.

The primary object of our invention is to provide a rotary or oscillatory pump which will lift liquid, as a lubricant or water, from a level lower than the pump, without priming, and maintain a constant pressure on the outgoing liquid. This is accomplished, in the simple form of pump, without valves or any obstructions which would make any appreciable difference in the efficiency of the pump, when encountering dirt, chips, sediment or other foreign matter held in suspension by the pumped liquid.

Another object of this invention is to provide a one-way pump of the rotary or oscillatory type with adjustable means that may be set to permit of the pump maintaining a predetermined pressure or head at the discharge side of the pump, and excessive pressure is automatically relieved without retarding the action of the pump.

A further object of our invention is to provide a pump that may have its pumping action reversed and in this type of pump there are automatically operated valvular members completely housed within the pump and requiring no attention whatsoever when reversing the operation of the pump.

The above are a few of the objects attained by our pump which may be characterized in the following particulars;

First, the pump includes a body containing one or more impelling tumblers, which are eccentrically disposed relative to cylindrical chambers of the body and which are adapted to oscillate vanes supported by the pump body and reciprocable in the tumblers. The vanes are tangentially disposed relative to the tumblers, in contradistinction to a radial disposition, and such arrangement provides a maximum capacity for the intake and discharge chambers of the pump.

Second, the construction of the pump is such that the tumblers and vanes may be standard for pumps of different pumping capacities, it being only necessary to provide pump bodies of different sizes and then in-

stall impelling tumblers side by side in the pump, each of which adds to the capacity without increasing the diameter of the pump or its speed, and in such a multiple unit pump there will be a more constant flow of liquid.

Third, with the impelling tumblers disposed to constantly contact with walls of the pump chamber, there is a minimum pressure on the impelling tumblers and practically no wear, as a film of liquid is constantly maintained between the walls of the pump chamber and the tumbler, such film of liquid contributing towards a perfect vacuum, especially when pumping heavy oils, asphalt and the like.

Fourth, the impelling tumblers are yieldably held relative to the walls of the pumping chamber so that the tumblers may recede under any predetermined pressure or when contacting with any obstruction in the liquid being pumped.

There are other novel points about the construction and operation of our pump which will be hereinafter specifically referred to, and reference will now be had to the drawings, wherein—

Figure 1 is a longitudinal sectional view of the one-way pump;

Fig. 2 is a cross sectional view taken on the line II—II of Fig. 1, showing parts of the pump in elevation;

Fig. 3 is a similar view of a reversible pump in accordance with our invention;

Fig. 4 is a horizontal sectional view taken on the line IV—IV of Fig. 3;

Fig. 5 is a longitudinal sectional view of a portion of the reversible pump taken on the line V—V of Fig. 3, and

Figs. 6 to 9 inclusive are diagrammatic views of the pump rotor in different positions.

Reference will first be had to Figs. 1 and 2 showing the one-way pump which has been extensively put into practice and found highly efficient for lifting liquids, particularly lubricants, and on account of the simplicity of construction entering into the pump, it may be constructed on a small scale for use inaccessible to other pumps.

The pump comprises a pedestal 1, bracket or the like by which the pump may be secured to a suitable support and the pedestal affords a long bearing 2 for a bushing 3 and a stuffing box 4, said stuffing box having an adjustable gland 5 held against accidental rotation by a latch 6 and from time to time

the gland 5 may be adjusted to compress or re-arrange any suitable packing within the stuffing box 4.

- 5 Journaled in the bushing 3 and the gland 5 is a drive shaft 6 which has one end thereof provided with a belt or power transmission wheel 7 by which the shaft 6 may be driven from a suitable source of power by a belt or other power transmission member.
- 10 It is obvious, however, that the drive shaft 6 may be coupled direct to an electric motor supported by the pedestal 1 or in proximity thereto so that the pump may be operated in a well or at some remote point from a
- 15 source of electrical energy or other power.

On that end of the bearing 2, opposite the stuffing box 4, is a circular head 8 cooperating with a detachable head or end plate 9 in supporting a pump cylinder 10, said cylinder being sandwiched between the heads 8 and 9 and connected thereto by screw bolts, tie rods or other fastening means.

20 The shaft 6 extends axially through a cylindrical chamber 11 of the cylinder 10 and into a bushing 12 provided therefor in a bearing 13 of the detachable end plate or head 9. The bearings 13 and 2 have lubricating ports 14 so that a suitable lubricant may be supplied to the bushings 3 and 12 by

25 any well known means.

That portion of the drive shaft 6, within the pump chamber 11, is rectangular in cross section, and is provided with pockets 15 for coiled expansion springs 16. Mounted on the rectangular portion of the drive shaft 6 to rotate therewith are one or more drive rings 17 which are eccentrically disposed on said shaft and have oblong openings 18 to receive the rectangular portion 30 of the drive shaft. The openings 18 are of greater area than the cross-sectional area of the shaft and opposed walls of the openings 18 engage opposed walls of the shaft so as to establish a driving relation between the rings 17 and said shaft but other walls of the openings 18 are in spaced relation to walls of the shaft so that the drive rings may shift from an eccentric relation to the shaft towards a concentric relation. The expansion 35 springs 16 abut end walls of the openings 18 and constantly maintain the eccentric relation of the drive rings to the shaft 6, yet permitting of the drive rings yielding when occasion so requires.

40 55 In case of one drive ring said ring corresponds to the length of the pump chamber 11, but when two or more drive rings are mounted on the drive shaft 6, said rings are proportioned so that the pumping 50 chamber 11 may be divided and this is accomplished by mounting one or more non-rotatable partitions 19 in the pump chamber 11. As shown in Figs. 1 and 2 there is a single partition having an opening 20

60 65 providing clearance for the rectangular por-

tion of the shaft 6, and said partition is snugly sandwiched between the drive rings 17 and tumblers 21 loosely mounted on the drive rings. The tumblers 21 are in the form of bands or sleeves having peripheries adapted to wipe the inner walls of the pump cylinder 10 and with the tumblers supported eccentrically of the pump chambers 11, by the eccentrically disposed drive rings 17, there will be a space for liquid 70 constantly between the walls of the pump chamber 11 and that portion of the tumbler peripheries that does not contact with the wall of the chamber 11, although a film of liquid may exist at the points of contact 75 between the tumblers and the chamber walls.

80 On the pump cylinder 10 is a longitudinally disposed enlargement 20* and at its juncture with the pump cylinder said enlargement has a longitudinal bore 21 communicating with the pump chamber 11 by a slot 22. The bore 21 is divided, similar to the pump chamber 11, by extensions 23 of the partitions 19 and as illustrated the single partition 19 is prevented from rotating in the pump chamber by reason of its extension. The partition may be mounted in the pump chamber from either end thereof and after being properly located the drive rings and tumblers may be assembled. Then, oscillatory vanes 24 are mounted in the ends of the pump chamber. Each vane is in the form of a blade corresponding in width to the division of the pump chamber and each vane extends through the slot 22 and has a barrel or tubular portion 25 loosely fitting in the bore 21 so that the vane barrel may rock in the bore and constitute a pivot for the oscillatory or pendulum like vane. The opposite end of the vane is reciprocable in a kerf or groove 26 tangentially disposed in the tumbler 21 and to prevent air or liquid from being trapped in the inner end of the groove 26, said groove may have a small port 27 leading to the periphery of the tumbler. We attach considerable importance to the tangential arrangement of the vanes 24, in contradistinction to a radial relation between the vanes and the tumblers, as larger intake and discharge chambers are maintained in the pump cylinders. When the pump includes two vanes, as shown, it is preferable to arrange the pumping units in opposed relation, as indicated by full and dotted lines in Fig. 2, thus providing opposed chambers which are receiving liquid and opposed chambers which are discharging liquid, this arrangement balancing the rotor of the pump and such balancing is more equalized as the number of pumping units is increased.

100 105 110 115 120 125 The enlargement 20* has a longitudinally disposed intake chamber 28 and a longitudinally disposed discharge chamber 29, these chambers being on opposite sides of

the bore 21 and communicating with the pump chamber 11 in proximity to the slot 22. Communicating with the intake chamber 28 is an inlet port 30 and communicating with the discharge chamber 29 is an outlet port 31 said ports being intermediate the ends of the chambers, as indicated by dotted lines in Fig. 1. The discharge chamber 29 and the intake chamber 28 communicate with a valve chamber 32 longitudinally disposed in a valve body 33 transversely of the enlargement 20, said valve chamber having a partition 34 affording communication between the chambers 28 and 29, and a seat 15 for a check valve which controls such communication. The check valve is in the form of a spring pressed plunger 35 slidable in an adjustable plug or guide 36 closing one end of the chamber 32, and the expansive 20 force of a coiled spring 37 encircling the plunger 35 retains the plunger normally seated against a predetermined pressure of liquid in the discharge chamber 29, but when there is an excessive pressure of liquid in the 25 discharge chamber the plunger 35 is unseated to permit of the excessive liquid flowing into the valve chamber 32 and the intake chamber 28 to the pump chamber 11. The adjustable plug 36 may be calibrated relative to the valve body so that the check 30 valve may be set to relieve a predetermined excessive liquid pressure on the outlet side or head of the pump.

Considering the operation of the one-way 35 pump, reference will be had to the diagrammatic views, Figs. 6 to 9 inclusive, showing different positions the tumblers 21 may assume in one stroke or cycle, assuming that the rotor or single tumbler is turning in 40 the direction indicated by the arrow. In Fig. 6 the tumbler is in its uppermost position surrounded by liquid in the pump chamber 11, presenting an undivided crescent shaped body of liquid by reason of the 45 tumbler contacting with the pump chamber wall contiguous to the slot 22. As the tumbler starts to turn in a clockwise direction, with a somewhat wiping action against the chamber wall, the body of liquid is transferred in a clockwise direction towards the 50 outlet side of the pump, and after a half revolution with the tumbler in the position shown in Fig. 8 the pump chamber has received liquid on its inlet side and is continuing to discharge on its outlet side, with the vane 24 cooperating with the tumbler in 55 providing two separate bodies of liquid. By reference to Fig. 9, showing a further turn of the tumbler it will be noted that more than one-half the volume of the pump chamber 60 has been drawn in, before the discharge side of the pump chamber is completely exhausted, consequently the pump is able, as shown in Fig. 8, to eventually discharge 65 more than one-half the volume of the pump

chamber and this is obviously due to the tangential mounting of the vane 24. This condition causes a steady stream to be discharged which would not be possible were the vane radially disposed, permitting an 70 equal volume on both sides. When there is an equal volume of liquid on both sides of the vane there is a distinct and marked pulsation in the liquid as the tumbler passes the intake and discharge chambers, and 75 such pulsation is entirely eliminated in our pump because of alternately maintaining intake and discharge volumes of liquid, one or the other being greater than one-half the volume of the pump chamber, in each 80 pump unit.

The movement of the tumbler relative to the vane is slightly accelerated, reaching its maximum when the tumbler is in the position shown in Fig. 7 where pressure is greatest and at its minimum when at the position shown in Fig. 6, where the pressure is reduced. This is a distinct advantage, as the tumbler approaches and makes contact with the chamber wall adjacent the ports at a 90 correspondingly low speed, and the tumbler also approaches the ports at what may be considered an angle corresponding to the angularity of the vane.

The vane 24 is offset relative to the geometric center of its pivot or hinge, and this is necessary in order to bring its juncture as close as possible to the central vertical plane of the pump. This permits of the slot 22 being made with straight and parallel sides 100 and of a width less than the diameter of the bore 21, yet sufficiently wide to allow the vane to oscillate freely. It is obvious that the restricted entrance to the bore 21 prevents accidental displacement of the vane 105 during its oscillatory movement.

Reference will now be had to Figs. 3 to 5 inclusive showing the reversible type of rotary pump and while the rotor is the same as in the one-way pump, the enlargement 110 has been changed to afford a plurality of valve chambers for automatic check valves. The enlargement is designated 38 and is provided with valve chambers 39, 40 and 41, the chambers 39 and 40 being disposed in 115 parallelism and the chamber 41 disposed at a right angle to the chambers 39 and 40 at one side or end of the enlargement. The chambers 39 and 40 have ports 42 communicating with a common outlet port 43 and the ports 42 are adapted to be closed by gravity seating check valves 44. The chambers 39 and 40 have end ports 45 communicating with the chamber 41 and said ports are adapted to be closed by check valves 46. 120 The check valves may be conveniently in the form of spherical bodies placed in the chambers 39, 40 and 41 through openings normally closed by screw plugs 47. Besides the chamber 41 communicating with 125

the chambers 39 and 40 it communicates with a common outlet port 47, and the chamber 39 communicates with the pump chamber 11 by a port 48 at the inlet side of the pump cylinder, and the chamber 40 communicates with the pump chamber 11 by a port 49 at the outlet side of the pump chamber.

In operation, one of the check valves 46 and one of the check valves 44 are normally seated when the rotor is driven in one direction; and when the rotor is driven in the opposite direction the other check valves are seated, the valves controlling the direction of liquid flow and no change or adjustment is necessary in connection with the pump when it is desired to reverse the operation thereof. As an instance of the operation of the check valves, considering the rotor to be turning in a counter-clockwise direction, the valve 44 of the chamber 40 will be unseated permitting liquid to be drawn through port 43 and port 42 into the chamber 40 and through the port 49 into the pump chamber where the liquid is forced out of port 48 into the chamber 39, the pressure of liquid therein seating the valve 44 in chamber 39 and unseating the valve 46 that controls the passage between the chambers 39 and 41, thus allowing the liquid to pass through chamber 41 and out of the port 47. Pressure of liquid within the chamber 41 will retain the other valve 46 seated, also the partial vacuum produced in the chamber 40.

It is thought that the operation and utility

of the pump will be apparent without further description and while in the drawings there are illustrated the preferred embodiments of our invention it is to be understood that the structural elements are susceptible to such variations and modifications as fall within the scope of the appended claim.

What we claim is:—

A liquid pump comprising a chamber having inlet and outlet ports and a bore between said ports, a partition in said chamber extending into the bore of said pump, a shaft concentric of said chambers, said shaft having a rectangular portion in each chamber provided with a pocket, an expansion spring in each pocket, a driving ring slideable on each rectangular portion of said shaft and pressed by the spring in each pocket, a tumbler loosely mounted on each driving ring at each side of said partition, and a vane at each side of said partition having a tubular portion pivotally held in the pump bore, and another portion slideable in each tumbler and actuated from a driving ring.

In testimony whereof we affix our signatures in the presence of two witnesses.
